(57) CLAIM

The ornamental design for a greeting card set, as shown and described.

DESCRIPTION

FIG. 1 is a top, front, right side perspective view of a greeting card set, showing our new design;

FIG. 2 is a bottom, rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front, right side perspective view thereof, showing the greeting card set in a partially assembled configuration; and,

FIG. 10 is a top, front, right side perspective view thereof, showing the greeting card set in a completely assembled configuration.

The broken lines in the drawings depict portions of the greeting card set that form no part of the claimed design.
